UNITED STATES PATENT OFFICE.

EDWARD PETERSON, OF ST. HILAIRE, CANADA.

SIGNAL SYSTEM.

SPECIFICATION forming part of Letters Patent No. 693,308, dated February 11, 1902.

Application filed July 5, 1901. Serial No. 67,182. (No model.)

To all whom it may concern:

Be it known that I, EDWARD PETERSON, of St. Hilaire, Province of Quebec, Canada, have invented certain new and useful Improvements in Signal Systems; and I do hereby declare that the following is a full, clear, and exact description of the same.

My invention relates particularly to railway signal systems, although it is applicable to with advantage to other uses.

The invention may be said, broadly speaking, to combine with a device adapted to support one or more train-order blanks removable means for retaining said train-order blank or blanks against displacement and means for operating a signal device while an order-blank is out of place. This removable means preferably consists of a lever which is operatively connected to a semaphore and adapted to operate said signal when the semaphore fails to respond to its lever.

More specifically speaking, the preferred embodiment of my invention may be said briefly to consist of a convenient box or receptacle for train-order blanks; also, the said box located immediately behind a semaphore or signal-board lever, which virtually locks its contents (the order-blanks) till the lever is raised from across it, this process putting the semaphore to "danger," thus preventing an operator accepting train-orders for delivery before it is so set; also, that when any of the order-blanks so released are extracted from the box an electric signal device gives warning should an attempt be made to lower the semaphore-lever before the object of the extracted order-blank has been accomplished and the blank returned to the box; also, that the electric signal will give warning if the semaphore does not properly respond to its lever.

For full comprehension, however, of my invention reference must be had to the accompanying drawings, forming a part of this specification, in which like symbols indicate the same parts, and wherein—

Figure 1 is a perspective view of a box constructed according to my invention and provided with my improved signal device, and Fig. 2 is a plan view with the box-top partly broken away.

The box *b* is preferably vertically arranged and has horizontal shelves *c* to support the

order blanks or tablets *d*. These shelves are preferably metallic, although, if desired, they can be made of wood, paper, or any other material furnished with suitable contacts instead. A vertical lever *e* is fulcrumed at its upper end, as at *f*, to the top *g* of the open front of the box and is of sufficient length to extend below the lowermost shelf, while the said lower end has a handle *g'*, and a perforated lug *h* upon the outside edge of the lever has one end of the chain *i* for operating the semaphore *j* connected thereto. A series of spring-contacts *k* are carried upon the rear 55 of the box, one in line with each metallic shelf and adapted to normally make contact therewith, and a single spring-contact *l* upon the top *g* of the front of the box is normally out of engagement with a contact *m* upon *g*. 60 A battery *n*, including a bell *o* in its circuit, has one pole connected by a wire *p* to the contact *m* and its other pole by a wire *q* to the electric bell *o* and thence to one of the metallic shelves through a perforation *q'* in the 65 side of the box, while the shelves and spring-contacts are all in electrical contact with one another through wires *r*, *s*, and *t*, respectively. The wire *r* leads across all the spring-contacts *k* and is electrically connected to each. 70 The wire *s* leads from one of these contacts *k* to the spring-contact *l*, and the wire *t* electrically connects all the shelves *c* together, the free end of spring-contact *l* being curled inwardly, as at *l'*. The lever *e* is fulcrumed 75 upon the forward end of a bracket *e'*, secured above the box and projecting a short distance over the front edge *g* thereof in order to cause the pull of the chain under the influence of the semaphore-spring to overcenter 80 the lever when down and hold it yieldingly but tightly against the forward end of the order-tablets, thereby pushing the latter against the spring-contacts *k* and displacing them from the shelves. A normally open short circuit 85 is formed by a pair of wires *u* and *v*, connected to the polar wires of the battery, and said short circuit includes a resistance-coil *w* and a switch *x*.

The chain connection between the lever and 90 semaphore and the spring-actuated means for operating the semaphore are and may be of ordinary and well-known construction.

The object of the short circuit is to enable

the operator after having received instructions to immediately close the circuit and allow it to remain closed until, with the bell ringing as a reminder, he carries out the instructions, when he can again open the circuit.

The operation of my invention is as follows: When the operator receives notification of being required to receive a train-order for delivery, he raises the lever and withdraws the particular order blank or tablet adapted to produce the required number of manifolds, as will be presently pointed out. He then writes his despatch, (the lever being maintained upheld by the semaphore mechanism,) and after fulfilling the object of it returns the tablet and lowers the lever. Upon the withdrawal of a tablet the particular spring-contact *k* bearing thereupon will be allowed to make a contact with the shelf, thereby closing the battery-circuit except for the contact *l*, which upon the raising of the lever will spring away from contact *m*. If the operator should then lower the lever without replacing the tablet, the contact *l* will be pressed toward the contact *m*, and immediately the curled end *l'* thereof touches the said contact *m* (which will be before the lever is overcentered, and consequently held by the semaphore mechanism) the circuit will be closed and the bell rung until the lever is again raised and the tablet returned to its place, after which the lowering of the lever will push the spring-contact *k* peculiar to the tablet from the shelf just as the contact *l* is about to touch the contact *m*, thus if the tablet is returned to its proper compartment preventing the bell-circuit being closed.

One of the main advantageous features of the above-described novel arrangement of the order-box immediately behind the lever is that the order-blanks cannot be removed from the box until the lever is lifted and the semaphore set at "danger," thereby insuring the stopping of any train which would otherwise pass while the order is being written out or the tablet is for other reasons out of place. The rear spring-contact can, if desired, be made of sufficient strength to automatically push the order-blank out far enough to cause a contact to be made between each contact and its shelf when the lever is raised.

At times it is necessary to make more than two copies of an order—as, for instance, when the same order is to be delivered to, say, two or more trains, in which case, if for two trains with one engine each, five copies will have to be made, one to be delivered to each engineer, one to each conductor, and one to be retained by the operator. To facilitate this, I provide the series of compartments shown, and the numerals therein indicate to what extent the order can be manifolded by the tablet in each compartment. The number of compartments can be increased or diminished according to requirements.

It is obvious that, if desired, the spring-

contacts *k* can be located at one or both sides of the box and each in such position as to insure the lifting thereof from the metallic shelf or contact thereon by a tablet as it is being slid into place.

My invention can with equal advantage be applied to systems comprising a horizontal lever; but in such case the lever would have to be provided with a cross-piece to perform the function of my present vertical lever, and the contacts themselves can be varied in their detail construction to a considerable extent without departing from the spirit of my invention.

What I claim is as follows:

1. The combination of a train-order box adapted to contain a series of order-blanks, removable means for retaining said train-order blanks against displacement, and means for operating a signal device while an order-blank is out of place.

2. The combination with a semaphore, of an order-blank-supporting device, a lever extending across and retaining the order-blanks in said device, and means for operatively connecting said lever to said semaphore to cause the semaphore to move to danger when the lever is moved away from the device.

3. The combination with a semaphore, of an order-blank box having a series of receptacles, a lever extending across said receptacles and retaining the order-blanks in same, and means for operatively connecting said lever to said semaphore to cause the semaphore to move to danger when the lever is moved away from the receptacles substantially as and for the purpose set forth.

4. The combination of a box having a series of shelves parallel to one another a bar extending transversely of said shelves; an electric contact upon each of said shelves; an electric battery; a wire connecting one pole of said battery to said electric contacts; an electric contact adjacent to said bar; a wire connecting the opposite pole of said battery to said last-mentioned electric contact; a contact normally out of engagement with said last-mentioned contact and movable with said bar to make contact with said last-mentioned contact when the bar is closed in adjacent to the shelves, and a wire connecting said movable contact to the first-mentioned pole of the battery, substantially as described and for the purpose set forth.

5. The combination with a semaphore-actuating lever, of means for operating a signal device when the semaphore fails to respond to its actuating-lever, said means consisting of an electric circuit including said signal device and having two breaks, one of said breaks being normally open and the other normally closed; means for closing said normally open break, and means for opening said normally closed break simultaneously when the lever is moved to actuate the semaphore; and means for again closing said last-mentioned break and with it the circuit when

the semaphore fails to respond to its lever, for the purpose set forth.

6. The combination with a semaphore-actuating lever of means for operating a signal device when the semaphore fails to respond to its actuating-lever, said means consisting of a pair of electrical contacts one normally in engagement with the other; a contact-breaker; said semaphore-lever being adapted 10 when down to retain said contact-breaker between said pair of contacts; an electrical contact adjacent to said lever when the latter is in its last-mentioned position; an electrical contact normally out of contact with said last-mentioned contact and movable with said lever into and out of contact therewith; means 15 electrically connecting the electrical contact movable with the lever to one of said pair of contacts; an electric battery one terminal 20 whereof is electrically connected to the contact adjacent to said lever and the other terminal whereof is electrically connected to the other contact of said pair and a signal device included in the circuit thus formed, for the 25 purpose set forth.

7. The combination with a semaphore-actuating lever of means for operating a signal device when the semaphore fails to respond to its actuating-lever, said means consisting 30 of a stationary electrical contact, a movable electrical contact normally engaging said first-mentioned contact; a contact-breaker; said semaphore-lever being adapted when down to retain said contact-breaker between 35 said stationary and movable contacts; a stationary electrical contact adjacent to said lever when the latter is in its last-mentioned position; an electrical contact normally out of contact with said last-mentioned contact 40 and movable with said lever into and out of contact therewith; means electrically connecting said stationary contacts together; means electrically connecting said movable electrical contacts together; an electric battery one terminal whereof is electrically connected to said stationary contacts, and the other terminal whereof is electrically connected to said movable contacts; and a signal device included in the circuit thus 45 formed, for the purpose set forth.

8. The combination with a series of electrical contacts arranged a short distance from one another; a second series of electrical contacts normally engaging said first-mentioned 55 series of contacts; a contact-breaker; a movable bar extending across the spaces between said first-mentioned series of electrical contacts and adapted, when adjacent to said contacts to retain said contact-breakers between 60 said first and second mentioned series of contacts; a single electrical contact adjacent to said bar when the latter is in its last-mentioned position; an electrical contact normally out of contact with said last-mentioned 65 contact and movable with said bar into and out of contact therewith; means electrically connecting said first-mentioned series of and

said single contacts together; means electrically connecting said second-mentioned series of and single movable electrical contacts 70 together; an electric battery one terminal whereof is electrically connected to said first-mentioned series of contacts, and the other terminal whereof is electrically connected to said contact movable with the bar; and a 75 signal device included in the circuit thus formed, for the purpose set forth.

9. The combination of a box having a series of metallic shelves parallel to one another a bare extending transversely of said shelves; an 80 electric contact normally bearing upon each of said shelves; an electric battery; a wire connecting one pole of said battery to said yielding electric contact; an electric contact adjacent to said box; a wire connecting the 85 opposite pole of said battery to said last-mentioned electric contact; an electric connection between said contact and shelves; a contact normally out of engagement with said last-mentioned contact and movable with said 90 bar to make contact with said last-mentioned contact when the bar is closed in adjacent to the shelves, and a wire connecting said movable contact to the first-mentioned pole of the battery, and a shunt-circuit including a resistance device, said battery, said bell and a normally open switch, substantially as described and for the purpose set forth.

10. The combination with a semaphore-actuating lever, of a train-order box having a 100 series of contact-shelves parallel to one another and extending transversely of said box, the front and rear sides of said box being open; a series of spring-contacts located at the rear of the box and normally bearing upon 105 and effecting electrical contact with said contact-shelves; a contact-piece upon the front edge of the box; a spring-contact normally out of contact with said contact-piece; an electric battery; an electric bell; a wire leading from one pole of said battery to one terminal of said bell; a wire leading from the other terminal of said bell and connected to each of said contact-shelves; a wire leading from the opposite pole of said battery to the 115 contact-piece upon the front of the box; a wire leading from the spring-contact at the front of the box and electrically connected to each of the spring-contacts at the rear of the box, said box being located behind and in 120 close proximity to the semaphore-lever substantially as described and for the purpose set forth.

11. The combination with a semaphore-actuating lever, of a train-order box having a 125 series of contact-shelves parallel to one another and extending transversely of said box, the front and rear sides of said box being open; a series of spring-contacts located at the rear of the box and normally bearing upon 130 and effecting electrical contact with said contact-shelves; a contact-piece upon the front edge of the box; a spring-contact normally out of contact with said contact-piece; an

electric battery; an electric bell; a wire leading from one pole of said battery to one terminal of said bell; a wire leading from the other terminal of said bell and connected to 5 each of said contact-shelves; a wire leading from the opposite pole of said battery to the contact-piece upon the front of the box; a wire leading from the spring-contact at the front of the box and electrically connected to 10 each of the spring-contacts at the rear of the box and a normally open short-circuit device

connecting the second and third mentioned wires, said box being located behind and in close proximity to the semaphore-lever, substantially as described and for the purpose 15 set forth.

In testimony whereof I have affixed my signature in presence of two witnesses.

EDWARD PETERSON.
